CAM FOLLOWER

Otto Bochmann, Remscheid-Lennep, Germany,
assignor to Barmer Maschinenfabrik Aktiengesellschaft, Wuppertal-Oberbarmen, Germany

Application September 19, 1936, Serial No. 101,648
In Germany November 28, 1935

4 Claims. (Cl. 74—55)

This invention relates to a thread guide drive, especially for centrifugal spinning machines for artificial silk, in which the drive transmission for the up and down movement of the loading frame 5 is effected by cam discs which are oscillatable for adjusting the stroke. As is known, it is necessary in centrifugal spinning machines to adjust the thread guide stroke according to the actual thickness of the thread so as to always obtain the same spinning cake height. For this purpose the oscillatable cam disc is provided, which enables a simple alteration of the thread guide stroke. In this thread guide drive the transmission from the oscillatable cam disc to the loading frame 15 is effected by employing a crowned roller engaging in a cam groove. The crowned construction of the roller alone enables an adjustment of the cam disc, otherwise the roller would jam in the cam groove. However, the crowned construction 20 of the roller always produces only a point contact with the cam disc. This is open to the objection that considerable wear occurs at this point and necessitates the replacement of this element after a short time. Apart from the resultant 25 continual expense the machine must be repeatedly stopped which is not permissible for the manufacturer.

The object of the invention is to overcome these objections. This is attained by employing 30 cylindrical rollers or guide blocks engaging in the continuous cam groove for transmitting movement between the cam discs and loading frames, these rollers or blocks being connected with the holder of the loading frame by a simple hinge 35 joint. This simple hinge joint ensures a perfect guiding of the guide block in the cam groove in the case of slight changes of pitch owing to the necessary play for fitting. However, in the case of considerable changes in pitch it is advisable 40 when employing guide blocks to connect this with the holder of the loading frame by a cross-joint so that it can adapt itself to any change of pitch.

The invention presents the advantage that 45 transmission means can be employed between the cam and loading frame, which means ensure at least a line contact and when guide blocks are employed even a surface contact without impeding the adjustment of the cam disc. By this 50 construction wear at this point is almost completely eliminated so that the former interruptions in working no longer occur and consequently the machines can be run economically. Moreover, expense by replacement of these elements is 55 eliminated as they last indefinitely.

Several embodiments of the invention are illustrated by way of example in the accompanying drawing in which—

Fig. 1 shows the employment of a guide block 5 in elevation.

Fig. 2 is a section on line A—B of Fig. 1.

Fig. 3 is a similar view to Fig. 1 of a modified form of construction.

Fig. 4 is a section on line C—D of Fig. 3.

Fig. 5 shows the employment of a cylindrical 10 roller.

Fig. 6 is a section on line E—F of Fig. 5.

In Figs. 1 and 2 the transmission of movement between the cam disc 1 and the loading frame 2 is effected by a guide block 3 which is connected 15 with the holder 5 of the loading frame by a simple hinge joint, it being mounted on a square 4 on the holder 5 of the loading frame and is pivotable about a bolt 6 fixed in the square by a pin 7. The swinging takes place over bevels 8 of the 20 square 4 so that the guide block can adapt itself to the actual position of the cam disc.

Figs. 3 and 4 show the same arrangement only 25 in this instance the guide block 3 is connected with the holder of the loading frame by a cross-joint in such a manner that it can adapt itself to any alteration in the pitch of the cam disc. For 30 this purpose the square 4 is loosely mounted on a bolt 9 fixed on the holder 5 and carrying the loosely mounted guide block on laterally projecting pins 10. In this manner a cross-joint is produced which allows the guide stone to move in all directions. For limiting the oscillating movement of the square together with the guide block 35 on the bolt 9, the bolt has a pin 11 which engages in a slot in the square limiting the oscillating movement.

In Figs. 5 and 6 a cylindrical roller 12 is employed which is mounted on a sleeve 13 which is 40 loosely mounted on a bolt 6 fixed in the square 4.

The thread guide drive can evidently be employed everywhere where continuous oscillatable tip curves are employed, that is also in spool spinning machines, ring twisting machines, twisting 45 machines and winding machines.

I claim:

1. A thread guide drive, especially for centrifugal spinning machines for artificial silk in which the drive transmission to raise and lower 50 the loading frames is effected by cam discs which are oscillatable to vary the stroke, comprising in combination with the loading frame and the cam disc and in which said cam disc has a continuous groove, a holder carrying said frame, a guide ele- 55

ment engaging in said groove having a line contact with the wall of the groove, and a hinge connection between said guide element and said holder constructed and arranged to produce an oscillating movement in one direction and to be guided in its movements in two directions with said guide element maintaining its original contact with the walls of the cam groove irrespective of the tiltable adjustment of the cam disc.

19 2. A thread guide drive as specified in claim 1,

in which the guide element consists of a cylindrical roller.

3. A thread guide drive as specified in claim 1, in which the guide element consists of a guide block.

4. A thread guide drive as specified in claim 1, in which the guide element consists of a guide block and the hinge connection consists of a cross-joint.
